United States Patent Office.

WILLIAM ANDERSON KERR, OF EASTON, PENNSYLVANIA.

Letters Patent No. 103,894, dated June 7, 1870.

IMPROVEMENT IN PRINTING-PRESSES.

The Schedule referred to in these Letters Patent and making part of the same

To all whom it may concern:

Be it known that I, WILLIAM ANDERSON KERR, of Easton, in the county of Northampton and State of Pennsylvania, have invented a new and improved Printing-Press; and I do hereby declare that the following is a full, clear, and exact description thereof, which will enable others skilled in the art to make and use the same, reference being had to the accompanying drawing forming part of this specification.

Figure 1 represents a front elevation of my improved printing-press.

Figure 2 is a plan or top view, partly in section, of the same.

Figure 3 is a vertical longitudinal section of the same, taken on the plane of the line $x x$, fig. 2.

Figure 4 is an inverted plan view of the same.

Figure 5 is an end elevation of the same.

Similar letters of reference indicate corresponding parts.

This invention relates to improvements in rotary presses for printing both sides of one sheet by one process.

The invention consists in the general arrangement of devices for operating the type-frames.

The invention also consists in the arrangement of carrying-bands placed around the cylinder and other rollers, for taking hold of and carrying the paper to the required places.

The invention finally consists in the combination of drums or platens and type-frames and a suitable transferring mechanism.

A, in the drawing, represents the frame of my improved printing-machine.

In it are the bearings of two horizontal drums or cylinders, B C, which are hung in the frame close together, as shown in fig. 3.

Upon the axles of the drums B C are mounted gear-wheels, a b, respectively, they being of equal diameter, and meshing into each other, so that the drums can only revolve in opposite directions, but with equal speed.

By means of intermediate gearing, c c, of suitable kind, motion is transmitted to one of the drums B C from the driving-shaft D.

In the ends of the frames are grooved tracks for the type-frames E and F, respectively. These type-frames are perfectly flat, and are set up vertically in the ends of A.

Each type-frame carries a vertical rack, d, at its outer face, the said rack meshing into a toothed wheel, e, which receives oscillating motion by means of a connecting-rod, f, from a swinging lever, g.

The ends of the frame A are, at their free ends, connected with each other by means of a bar, h.

This bar is, by a rod, i, connected with a cog-

wheel of the train c, and is, as said wheel revolves, moved up and down in slotted vertical guides of the frame A. The bar h, by swinging the levers g, imparts the required reciprocating motion to the frames E and F.

The paper to be printed is first placed upon the drum B, onto a set of flexible bands, j j, that pass around the same.

These bands j are laid around the drum B, and around a smaller roller, l, which is held close to the inner side of the drum C.

The latter drum carries similar bands, m, which pass around rollers, n o, the latter being under the drum B, so that, from l to o, the bands j m are close together.

A third set of bands, p, is arranged under the drum C, passing over rollers r r, of which one receives rotary motion by means of a pinion, s, from the train c.

The paper to be printed is, as above stated, first placed upon the drum B, and is on the same held by the fingers t t, and carried against the type-frame E, on which its outer face is printed.

Then the paper is, between the bands j and m, carried toward the drum C, and is on the same fastened by other fingers, t' t', which hold it while its unprinted side is brought against the type-frame F, and printed by the same.

From the drum C the paper is taken to the band p, by which it is carried to the discharge-fingers u on a rock-shaft, G.

The rock-shaft is, by a crank, r, and a link, w, connected with a lever, z, which is pivoted to the frame A, and which, when turned by a pin, y, of the drum B, causes the shaft G to turn, so as to swing the fingers u down.

Whenever the paper, after having been printed on both sides, falls upon the fingers u, the latter are swung down to discharge the same.

A spring, z, throws the shaft G and fingers u up again into the original position.

The fingers t t are, as usually, fastened to shafts, H, pivoted in the drums B C, and operated by fixed stops, a', of the frame A.

Each type-frame has the type b' in its upper part, while its lower part, c', is made in form of a smooth inking-plate.

This plate c', passing along the surface of an inking-roller, d', becomes inked thereby, transferring the ink, during the upward motion of the type-frame, to an upper roller, i, which is hung in the frame A.

During the next downward motion of the type-frame the ink is transferred from the roller i to the face of the type. The roller d' receives the ink, by suitable intermediate rollers, from the ink-vat J.

Having thus described my invention,

I claim as new and desire to secure by Letters Patent—

1. The racks *d*, wheels *e*, rods *f*, levers *g*, and bars *h*, all combined with the reciprocating type-frames, to operate the same, substantially as herein shown and described.

2. The bands *j m*, arranged on and in combination with the drums *B C*, substantially as herein shown and described, to convey the paper in the manner described.

3. The drums *B* and *C*, combined and arranged with the plates *E* and *F*, and provided with any suitable transferring mechanism, all operating as described, whereby the sheets of paper may be printed on both sides during their passage through the press, as specified.

WILLIAM ANDERSON KERR.
